UNITED STATES PATENT OFFICE.

LOUIS C. LOEWENSTEIN, OF LYNN, AND HARVEY N. DAVIS, OF CAMBRIDGE, MASSACHUSETTS, ASSIGNORS TO GENERAL ELECTRIC COMPANY, A CORPORATION OF NEW YORK.

BOILER.

Application filed March 22, 1919. Serial No. 284,383.

To all whom it may concern:

Be it known that we, LOUIS C. LOEWENSTEIN, a citizen of the United States, residing at Lynn, county of Essex, State of Massachusetts, and HARVEY N. DAVIS, a citizen of the United States, residing at Cambridge, county of Middlesex, State of Massachusetts, have invented certain new and useful Improvements in Boilers, of which the following is a specification.

The present invention relates to boilers, especially those intended for vaporizing fluid having a high boiling point with respect to water and more especially to heavy fluids, such as mercury for example. In such a boiler many problems of a complex character are presented which are not found in ordinary steam boilers.

The object of our invention is to provide a boiler of improved construction and one which is efficient in operation.

For what we believe to be novel and our invention, attention is directed to the accompanying description and the claims appended thereto.

In the accompanying drawings, which are illustrative of our invention, Fig. 1 is a vertical section of a mercury boiler, together with preheaters for the mercury and super-heaters for the mercury vapor and also for steam; Fig. 2 is a plan view of the same with certain of the parts in section; Fig. 3 is a section taken on line 3—3 of Fig. 4; Fig. 3^A is a detail sectional view of a part of one of the boiler grids or cells; Fig. 4 is a view of a boiler grid or cell in elevation with certain of the parts broken away; Fig. 5 is a view in side elevation of a number of boiler grids or cells, and Figs. 6 to 10 inclusive are detail views of different parts of the boiler.

It will be helpful to an understanding of the invention if it be borne in mind that the boiler is primarily intended for use in a power generating system in which the mercury vapor is used to drive a turbine or other prime mover and the exhaust therefrom employed to generate steam from water

which in turn is supplied to a turbine or other prime mover preferably of the condensing type, said turbines driving electric generators or other apparatus.

Briefly stated, in carrying out the invention, a plurality of grids or cells is provided which are supported within an enclosing casting in a manner to reduce heat strains to a minimum. The grids are all alike and each comprises two thin sheets of metal slightly separated to form liquid and vapor spaces. The sheets are sealed around their edges as by welding, electrically or otherwise where the liquid enters and the vapor is discharged. As thin sheets would bulge or buckle under pressure and heat they are united at a very large number of points scattered over their entire surfaces which has the effect of making them quite rigid and preventing bulging. This can readily be done in a variety of ways, as for example, by forming projections on one or both sheets and spot welding them. If liquid mercury were permitted to enter the grid at the bottom and escape at the top without any control of its movement the grid or cell would, of course, function as a boiler element but not very efficiently. To insure effective circulation partitions are located between the sheets of the grid, and they are so arranged that the mercury and vapor must flow a certain predetermined path or paths which bear a definite relation to the path or paths of the flue gases. As arranged the liquid mercury is caused to flow along the bottom of the grid and as vapor is formed it flows upward for a predetermined distance and is then caused to flow downward toward the fire and then upward to the point of escape. In other words, the vapor has to make three passes before leaving the grid. In general, it is preferable to subdivide the vapor at some stage and cause it to discharge through two or more paths in multiple.

The flue gases are also caused to follow a predetermined path or paths which bear a very definite relation to the path of the vapor. To provide space for the flue gases

the grids must be separated from each other and this is done by placing separators between them, which separators may be constructed in a variety of ways. They are 5 preferably made in the form of partitions and are employed to form definite flue gas passages. As arranged hot gases from the furnace enter the flues at the bottom, pass upward to the top of the grids and are then 10 turned and caused to flow downward to a point near the bottom and finally escape by lateral passages into an outer compartment. In other words, the flue gases make a double pass in flowing from the furnace 15 to the point of escape. During the first portion of their path they flow in the same direction as the mercury vapor but in the latter part they flow in the opposite direction and in this manner are caused to give 20 up the greater part of their heat. Since the gases contain a large amount of heat after evaporating the mercury, a necessary evil due to its high boiling point, they may 25 advantageously be employed to superheat the mercury vapor, preheat the mercury and superheat steam when the latter is used in a portion of the complete cycle.

The sheet or plate construction for the grids or cells has the advantage that the 30 parts may be stamped out of sheet stock at a small expense after the dies are made and said dies are of simple construction. The plate construction also results in a rapid transfer of heat from the flue gases to the 35 liquid in the cell or grid. This rapid transfer of heat is due not only to the thin walls of the grids but also to the fact that the liquid and the vapor released thereby flow through the grids in relatively wide and 40 very thin streams. The use of welded buttons, indentations or equivalents securing devices not only provides separators between the sheets but affords a simple means 45 for uniting the sheets and adds greatly to their mechanical strength. By combining a mercury preheater element with each grid or cell it can be formed at the same time the sheet is formed and this results in a 50 considerable simplification of the structure as a whole. Furthermore, by making all grids alike, they can be replaced quickly and economically in the event of injury.

Instead of employing individual separators between the grids or cells to form flue 55 gas spaces the plates themselves may be ribbed or corrugated or otherwise formed so that when assembled into the complete boiler the ribs or corrugations act as separators. This has the advantage that the 60 separators also serve as strengthening ribs for the sheets and the use of separate attaching means is avoided thus materially reducing the cost of construction and greatly simplifying it. In order to reduce the 65 amount of heat insulation as much as pos-

sible a double casing is provided for the boiler, and the air which supports combustion flows between the two casings before entering the burner.

Referring to the drawings, 21 indicates 70 a boiler casing of any suitable construction which is suitably lagged at 21^a to prevent the escape of heat. Inside the casing is a plurality of boiler grids 22 each comprising two sheets of metal suitably united as by 75 welding along their edges to form spaces or passages for the liquid mercury and the vapor due to evaporation thereof. These grids are placed side-by side and are supported by suitable means such as the through 80 bolts 23 which pass through ears 24 in the grids and are supported by the walls of the boiler casing. In other words the grids are hung on these bolts and are free to expand 85 and contract in all directions in accordance with temperature changes, without causing undue stresses. Below the grids is a burner or furnace 25 of suitable construction. In this case it is shown as a gasolene burner to which fuel is supplied at one or more points 90 by a suitably arranged pipe 26. Air to support combustion is supplied from the air chamber 27 which completely surrounds the boiler grids and is formed by the inner casing wall 28 and the outer wall 21. This 95 arrangement causes the air admitted to the furnace to be preheated and in this manner additional heat is extracted from the flue gases. The exhaust products of combustion escape from the inner casing by the outlet 100 or stack 29. Air may be forced into the chamber 27 under pressure to afford the necessary draft or the stack 29 may be connected to a suitable chimney for the purpose. Located within the inner casing is a 105 superheater 30 for the steam evaporated from the water used as the condensing agent for the mercury vapor after it has done work, as for example, in a mercury turbine. The superheater is composed of a number 110 of units of which two are shown and located on opposite sides of the grids. As shown each unit comprises a coil of pipe or pipes but it may be made in a variety of ways. Steam is admitted by the pipe 31, Fig. 2, 115 flows upwardly through the two opposite sections of the steam superheater in multiple, and is finally discharged through pipe 32.

The boiler grids are separated from each 120 other by small vertical flues 33 which are relatively thin and wide and through which the gases flow at a rapid rate. These flues are formed by central partitions 34 and other partitions 34^a on opposite sides thereof, said partitions taking the form of ribs on opposite sides of each sheet. The ribs may be formed on one or both sheets. It is advantageous to form them on both sheets 125 because the metal will not have to flow so 130

much under the die and hence the grid may be more easily formed. The hot flue gases from the burner first flow upwardly between the partitions 34 and 34^a and then turn and flow downwardly between the partitions 34^a and the outer walls which in this case are formed by mercury preheaters 34^b, the construction of which will appear more fully later. These preheaters or side walls have outlet openings or passages 35 (Figs. 1 and 4) between them near the lower ends to permit the hot gases to enter the steam superheating chambers through which they pass upwardly to the stack 29. The path of the flue gases is indicated by the full line arrows and it is to be understood that similar passages are provided between each pair of boiler grids. The flue gases are prevented from escaping at the top of the grids by flanges 51 and 53 on the sheets, Figs. 8 and 9, and by a layer or covering of insulating material 36^a, best shown in Figs. 4 and 5.

The mercury vapor generated within the grids flows ultimately into the superheater 37 which extends across the top of the grids and is connected to the vapor spaces thereof. These spaces are indicated at 38 in Fig. 2. From the construction described it will be apparent that the several grids feed mercury vapor to the superheater in multiple. Preheated mercury is supplied to each of the grids from opposite sides by individual preheaters 34^b and the latter are connected in multiple to headers as will appear more fully later. Superheated mercury vapor is discharged to the turbine by the outlet pipe 39. The superheater is subjected on its under side to the flue gases which pass upwardly between the grids and on its upper side to the hot gases as they flow to the stack 29. It will be seen from the foregoing that the flue gases are caused to give up their heat in vaporizing the mercury; in preheating the mercury; in superheating the mercury; in superheating steam, and in preheating the air passing to the burner through the chamber 27. In this manner the heat of the gases is effectively utilized and very little permitted to escape through the outer casing. Under some circumstances it will be possible to utilize the heat from the gases leaving the stack 29 to heat the feed water supplied to the steam portion of the complete cycle.

The specific construction of the boiler grid will now be described. Each grid comprises two thin sheets of metal 42-43, Figs. 3, 6 and 9, which are welded electrically or otherwise along their edges except for the portions forming the inlets from the preheaters and the outlets 38, Fig. 2, leading to the superheater. To prevent the plates from buckling as they otherwise would do and also to form definite spaces for the liquid mercury and the vapor thereof, we first provide partitions or separators between the

plates such as 44 and 45, shown in dotted lines, Fig. 4. The partitions 44 are substantially L-shaped in form and liquid mercury from the preheaters 34^b enters the boiler space below the partitions where the gases are hottest, being directly above the burner, and as vapor is formed it flows upwardly between the vertical portions of said partitions as indicated by the dotted line arrows in Fig. 4, then downwardly between the partitions 44 and 45 after which it turns around the lower end of the partition 45 and flows upwardly through the outlets 38 to the superheater 37.

As previously indicated the plates of the grids are very thin and to prevent them from separating they are electrically spot welded over their entire surfaces as indicated at 52, the small crosses and circles in Fig. 4 indicating the welds. These welds should be of small area so that the heat of the flue gases at the points of metal contact can be readily absorbed by the mercury. If the welds are too large or the vapor passage is unduly restricted at or near these welds the plates will be burned out for the temperatures are very high and the metal forming the sheets very thin.

To form the mercury preheater and also the partitions between adjacent grids the sheets 42 and 43, Figs. 3 and 6, are provided with projections or ribs 34, 34^a and 34^b and the edges of the sheets are welded together at 46. The grids when assembled are so arranged that corresponding ribs engage and in this manner vertical flue spaces 33 are formed. The spaces for the mercury vapor are indicated at 48 and it will be seen that they are very thin but relatively wide and due to this arrangement the heat of the flue gases is very readily given up to the mercury. The lower end of the outer rib, partition or separator 34^a is pinched or welded at the point 49, Figs. 3^a and 4, to prevent the mercury from the preheater from short circuiting its main path. Each grid has its own preheaters 34^b, one on each side, the walls of which are integral with the sheets, and the upper ends of which terminate in a header 49^a which is common to all of the preheaters on that side. The joints between these parts should be welded to insure fluid-tight connections. The relation of the header and the preheaters is well illustrated in Figs. 4, 5, 7 and 10. Fig. 7 clearly shows the supporting ears 24 for the grids and the supporting bolts 23 on which they are hung. To separate the sheets 42, 43 of each grid along their beveled upper edges inclined spacers 50 are provided which may be welded to the sheets or formed integral therewith. The sheets at this point have flanged edges 51, Fig. 9, and these are also united by welding. Over the edges of these flanges is placed a body of insulation 36^a

which prevents the free escape of heat and also serves to cover up any spaces between grids which may have been left in the welding operation and to this extent helps to define the flue gas passages or spaces.

Fig. 6 shows one of the boiler grids in section and specifically shows how the spot welds 52 are formed. As shown one of the sheets is provided with a series of buttons 52^a which are small in diameter and in addition to forming welding points also serve as separators to form the mercury vapor spaces. When properly welded the buttons also serve as means to reinforce the sheets and keep them from buckling.

Fig. 8 shows the mercury vapor superheater 37. The sheets at this point have outward turned edges or flanges 53 which are welded to a plate 54 forming the bottom wall of the superheater. In the plate are openings registering with the vapor spaces 38. The upper wall 55 of the superheater is also welded to the plate 54.

Our improved boiler has many advantages, among others that of a small storage space for the relatively costly fluid. Further, the heating surfaces are made of very thin metal which makes the boiler light in weight for a given output. By the arrangement of the various passages for the fluid, vapor and flue gases, we obtain a very rapid transfer of heat from the gases to the fluid and its vapor and also a very rapid circulation of both the fluid and the vapor which latter obviates the danger of burning out the heating surfaces. The liquid in the boiler is confined in very narrow spaces or passages and is subjected to very high temperature, the advantage of which as we have demonstrated in experiments is that the generation of vapor is explosive in character with the result of completely atomizing any liquid particles which may exist in the vapor stream. This is an important factor in the transfer of heat from the flue gases to the liquid. As previously stated the boiling point of the fluid is high compared with that of water and hence the flue gases even after the vapor is formed contain a substantial amount of heat but by arranging the parts as described, this heat is utilized in a manner to substantially improve the efficiency of the boiler unit as a whole.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States,

65 is:—

1. In a boiler, the combination of a casing, a plurality of grids each comprising a pair of sheets of thin metal united along their edges, separators between the sheets forming definite liquid and vapor spaces, means separating the grids to form passages for the flue gases, a super-heater into which the grids discharge vapor, and which is supported by the grids and heated by the flue gases, means for supporting the grids within the casing, an inlet for feeding liquid to each of the grids, and an outlet for the vapor which communicates with the super-heater.

2. In a boiler, the combination of a casing, a plurality of grids, each comprising thin sheets of metal having a liquid and vapor space therebetween, projections on each pair of sheets which when assembled cooperate to form a preheater, the said sheets being welded along the edges outside of the preheaters and also between the preheater and the vapor space, means separating the grids to form flue gas spaces, a conduit admitting liquid to the preheater, and a conduit receiving vapor from said vapor spaces.

3. In a boiler, the combination of a casing, a plurality of grids, each comprising thin sheets of metal having a liquid and vapor space between, projections on opposite sides of each pair of sheets which when united form preheaters for the fluid, the projections on one grid engaging those on adjacent grids when the parts are assembled and forming the boundary walls of the flue gas passages, additional separators between the grids which also assist in defining the flue gas passages, and conduits conveying liquid to the grid and vapor therefrom.

4. In a boiler, the combination of a casing, a plurality of grids, each comprising thin sheets of metal having liquid and vapor spaces between, preheaters for the liquid formed by the sheets along certain of their edges, there being flue gas passages between the grids, and means for supporting the grids within the casing by one end so that said grids and the preheaters can freely expand and contract with temperature changes.

5. In a boiler, the combination of a casing, a plurality of grids, each comprising thin sheets of metal having liquid and vapor spaces between, said sheets having outwardly extending projections which when the parts are assembled form preheaters for the liquid and also separators to form flue gas passages, and rods supported by the casing and upon which the grids are supported near one end to permit of free expansion and contraction.

6. In a boiler, the combination of a plurality of sheet metal grids, each comprising a pair of thin metal sheets, individual pre-heaters for each grid located on opposite

edges and communicating with the spaces between the sheets, spacers between each pair of sheets forming liquid and vapor spaces, separators between the grids forming flue gas spaces, a super-heater mounted directly on the grids and welded to said sheets and into which the grids discharge vapor in multiple, and headers for supplying liquid to the pre-heaters.

In witness whereof, we have hereunto set our hands this 20th day of March, 1919.

LOUIS C. LOEWENSTEIN.
HARVEY N. DAVIS.

edges and communicating with the spaces between the sheets, spacers between each pair of sheets forming liquid and vapor spaces, separators between the grids forming flue gas spaces, a super-heater mounted directly on the grids and welded to said sheets and into which the grids discharge vapor in multiple, and headers for supplying liquid to the pre-heaters.
